UNITED STATES PATENT OFFICE.

URIAH CUMMINGS, OF NEW HAVEN, CONNECTICUT.

PULVERIZING-MACHINE.

SPECIFICATION forming part of Letters Patent No. 478,253, dated July 5, 1892.

Application filed November 27, 1891. Serial No. 413,209. (No model.)

To all whom it may concern:

Be it known that I, URIA CUMMINGS, a citizen of the United States, residing at New Haven, in the county of New Haven and State 5 of Connecticut, have invented new and useful Improvements in Pulverizing-Machines, of which the following is a specification.

This invention relates to the class of machines which are employed for pulverizing 10 or reducing cement, ores, and other hard substances.

My invention has for its objects to construct a compact and durable pulverizing-machine of large capacity; to so organize the machine 15 that the parts which are subjected to wear can be readily removed and replaced when necessary, and finally to provide the feed-hopper of the machine with simple means for regulating and cutting off the flow of the material to the pulverizing devices.

In the accompanying drawings, consisting of three sheets, Figure 1 is a side elevation of my improved pulverizer. Fig. 2 is a vertical cross-section thereof in line $x x$, Fig. 1. Fig. 25 3 is a longitudinal sectional elevation of the machine, a portion of the driving-shaft of one of the rotary grinding-disks and the driving-pulley and bearings of said shaft being omitted. Fig. 4 is a face view of one of the 30 rotating grinding-disks on an enlarged scale. Fig. 5 is an enlarged rear view of one of the stationary grinding-disks. Fig. 6 is a face view of said stationary disk. Fig. 7 is an end view on an enlarged scale of one of the rings 35 whereby the stationary grinding-disks are clamped against the casing of the machine. Fig. 8 is a side elevation of said ring.

Like letters of reference refer to like parts in the several figures.

40 A represents the casing of the machine provided at its base with flanges a , whereby it is secured to beams A' or other supports. The casing is formed in its upper portion with a vertical throat or passage B , with which is 45 connected a feed-hopper C , surmounting the casing.

D D are upright stationary grinding disks or rings secured to opposite ends of the casing A, and E are rotary grinding-disks arranged 50 opposite the stationary disks and mounted, respectively, upon independent horizontal driving-shafts ff . These shafts are journaled in bearings F , secured to the beams A' , and each shaft is provided with a driving-pulley F' . Each stationary grinding-disk is formed 55 with a central opening or eye d and has its face provided with radial grinding ribs or teeth or any other suitable dress. The casing A is provided in opposite ends with openings g , which coincide with the eyes of the stationary grinding-disks.

$h h$ are inclined deflecting-surfaces, which slope from a transverse ridge h' in the middle of the case to the lower edges of the openings g , so as to direct the descending material laterally in opposite directions to and through the eyes of the stationary grinding-disks. Each of these stationary disks is provided on its rear side near its lower edge with an arc-shaped or semicircular rib or tenon i , 70 which fits into a corresponding groove i' , formed in the adjacent face of the casing. This rib i projects downwardly and the groove i' is undercut, as shown in Fig. 3, so as to prevent withdrawal of the rib from the groove, 75 except by raising the disk sufficiently to allow the rib to clear the lower undercut edge of the groove. The upper portion of the stationary grinding-disk is clamped against the end of the casing A by a ring k , which is provided 80 at its rear or inner edge with lugs k' , which bear against lugs or ears l , projecting radially from the rim of the stationary disk at its top and sides. This clamping-ring surrounds the rotary grinding-disk at a suitable distance 85 therefrom, and is held against the lugs of the stationary disk by a curb M , inclosing the pair of grinding-disks and secured to the end of the casing by screw-bolts m . The curb M is formed with an internal annular shoulder 90 m' , which bears against the outer edge of the clamping-ring k , so that upon tightening the bolts of the curb the lugs of the ring are forced inwardly against the lugs of the stationary grinding-disk, causing the ring to 95 clamp the disk tightly against the end of the casing. This construction forms a very simple fastening, which dispenses with the use of bolts or similar fastenings and permits the stationary disk to be readily secured in place. 100 The ring k also serves as a wearing-surface, which receives the impact of the pulverized material, which is discharged from the periphery of the grinding-disks. This ring and

the stationary grinding-disk are preferably formed of chilled iron. When the ring is worn out, it is readily replaced by a new ring upon removing the curb M. In order to enable the 5 ring to be removed and replaced without disturbing the shaft, the ring is split, as shown in Fig. 8, so that it can be sprung over the shaft. The curbs M are provided with stuffing-boxes for the passage of the driving-shafts.

10 Each rotary grinding-disk is provided with a removable face-plate N, made of chilled iron and having a suitable dress or grinding-surface. The face-plate is secured to the face of the rotary disk by bolts or other fastenings, 15 so that it can be readily removed when it becomes unserviceable from excessive wear, thereby avoiding the necessity of replacing the entire grinding-disk. The grinding-faces of the stationary and rotary disks approach 20 each other from the eye of the stationary disk to the peripheries of the disks, at which latter point they are arranged so closely together that the pulverized material is reduced to the desired degree of fineness when it is discharged from the peripheries of the disks. 25 Each shaft is preferably provided at its outer end with an adjusting device N' by which the rotary disk can be adjusted toward and from the stationary disk.

30 The casing A is provided with an inclined or hopper-shaped bottom O, which receives the pulverized material and from which the latter is conducted to a suitable receptacle by a spout O', the casing being provided below 35 the lower edge of the stationary disk with slots P, through which the material passes from the curb into the receiving-hopper.

q q are pivoted gates or valves arranged in the throat of the casing, and whereby the flow 40 of the material to the grinding-disks may be regulated or cut off. These feed-gates are secured upon transverse rock-shafts r r, journaled in the sides of the casing and provided with arms r' for turning the shafts.

45 S is a hand-lever formed at its inner end with a cross-head s, which is pivoted at its center to the outer side of the casing A. The outer ends of the arms r' are connected with opposite ends of the cross-head s by rods or 50 links s'. Upon swinging the hand-lever in one or the other direction its cross-head causes the links s' to move the arms of the rock-shafts r inwardly or outwardly simultaneously, thereby swinging the depending feed-gates 55 toward or from each other and restricting or enlarging the passage in the throat of the casing. The feed may thus be regulated as desired, or it may be entirely shut off by swinging the feed-gates against each other, as shown 60 by dotted lines in Fig. 1.

The material supplied to the feed-hopper descends in the throat of the casing and is directed by the inclined surfaces h between the faces of the grinding-disks by which it is 65 crushed and ground. As the two rotating disks are mounted upon the inner ends of two

independent shafts an unobstructed space is formed above the transverse saddle, which is composed of the inclined deflecting surfaces h. This open space lies directly underneath 70 the throat and the material to be ground enters this open space freely and then passes down the inclined sides of the saddle into and through the eyes of the stationary grinding disks, which eyes are also unobstructed, so as 75 to permit the material to enter freely. The weight of the material in the throat and feed-hopper presses directly upon the material in the eyes of the disks and insures a constant and uniform feed. The pulverized material 80 is discharged at the periphery of the disks, a portion thereof falling directly into the receiving-hopper O, while the remainder is thrown against the surrounding ring k, from which it passes into the curb and thence into 85 the receiving-hopper through the slots P. As the rotary disks run in close proximity to the stationary disks none of the material can escape until it has been reduced to the desired degree of fineness. The material is thus pulverized to a uniform degree of fineness by a 90 single passage through the machine.

My improved pulverizer is very simple in construction, has a very large capacity, and is especially desirable for pulverizing cement, 95 phosphates, ores, and other hard substances.

In the drawings a double machine having two pairs of grinding-disks is shown; but, if desired, a single pair of disks may be employed.

I claim as my invention—

1. The combination, with the stationary case provided in its upper portion with a vertical throat or passage and in its end with an opening communicating with said throat, of 105 a stationary grinding disk or ring secured to the case around said opening, a rotary grinding-disk facing the stationary grinding-disk, a curb or casing inclosing said disks, and a removable wear-ring surrounding the disks 110 and arranged on the inner side of the curb for receiving the impact of the pulverized material escaping at the peripheries of the disks, substantially as set forth.

2. The combination, with the case, of a removable grinding-disk applied to the end of the case, a curb removably secured to the end of the case and surrounding the grinding-disk, and a clamping-ring interposed between 120 said grinding-disk and the curb, whereby the disk is removably held in place on the case, substantially as set forth.

3. The combination, with the case having a groove in its end, of a removable grinding-disk applied to the end of said case and provided on its rear side with a rib or tenon entering said groove and at its marginal edge with lugs, a curb inclosing said disk and secured to the case, and a clamping-ring interposed between said curb and the lugs of the 130 grinding-disk, substantially as set forth.

4. The combination, with the casing con-

structed with circular openings in its sides, a central feed-throat communicating freely with said openings, a transverse saddle having its inclined sides extending to the lower edges of 5 said circular openings, stationary grinding-disks surrounding said openings, and a discharge-passage underneath said saddle, of separate shafts arranged on opposite sides of the case, rotary grinding-disks secured to the

inner ends of said shafts, and curbs inclosing 10 the grinding-disks, substantially as set forth.

Witness my hand this 23d day of November, 1891.

URIAH CUMMINGS.
